DESIGN FOR AN ADJUSTABLE INITIAL INDICATING BADGE OR SIMILAR ARTICLE

Harry B. Cohen, New York, N. Y.

Application June 21, 1935, Serial No. 57,364

Term of patent 3½ years

To all whom it may concern:

Be it known that I, Harry B. Cohen, a citizen of the United States of America, residing in the city of New York, county of New York, State of New York, have invented a new, original, and ornamental Design for an Adjustable Initial Indicating Badge or Similar Article, of which the following is a specification, reference being had to the accompanying drawing, forming part thereof, wherein indicating badge or similar article, showing my new design.

Fig. 2 shows a side elevational view with the small hand or pointer in a different position than shown in Fig. 1.

I claim:

The ornamental design for an adjustable initial indicating badge or similar article, substantially as shown.

HARRY B. COHEN.
